5 Claims. (Cl. 220—71)

This invention relates to the transportation of liquids in large volume and at low temperature. It relates more particularly to the structure of suitable tanks or containers for use as independent cargo vessels to be carried in transportation by means such as a ship or the like.

Containers or tanks of the type embodying the features of this invention are adapted for use in applications such as described in the copending application Ser. No. 582,965, filed May 7, 1956, wherein a cluster of such tanks or containers, as illustrated in Figure 1 of the drawing, are arranged in closely spaced apart relation within the hold of a ship or the like conveying means for transportation from place to place. Unlike land storage or transportation, the pitch and roll of a ship causes such shifting movement of the effective load of cargo carried within the tanks that problems peculiar to on-ship transportation develop. In general, it can be assumed that the shifting of load responsive to the pitch or roll of a ship becomes somewhat uniformly distributed about the walls of the tank when the latter is formed of cylindrical shape. However, the volume of liquid capable of being carried within a limited space is an important factor in the commercial practice of the entire program and, for such purpose, cylindrical tanks have been found to be impractical because of the large waste in space between the tanks.

Maximum utilization of available space can be effected more by the use of independent cargo containers of polygonal shape, as represented by tanks of square, rectangular, or trapezoidal design, as illustrated in the drawings, the selection of shape depending upon the dimensional characteristics of the space between the walls and the bulkheads of the ship. The difficulty which arises in the use of such tanks of polygonal or prismatic shape for the storage and transportation of large volumes of liquid resides in the means for providing sufficient structural strength for service as independent cargo containers; that is, the ability to hold the liquid within the tank without depending upon the structure of the ship itself for aid in support of the tank.

The situation under such circumstances is further aggravated by (1) the roll and pitch of the ship which creates unbalanced pressure in one or the other of the walls of the tank, and (2) the thermal gradient which exists throughout the length of the tank, especially when the latter is only partially filled with liquid having a temperature of -44° F. or lower. This thermal gradient is brought about by the fact that, when the tank is only partially filled, the portion of the tank above the liquid level will be at a higher temperature than the portions in contact with the liquid itself, thus creating a gradient from the top of the tank to the liquid level which may amount to as much as 260° F. when, as in the preferred practice, the content material in the tank constitutes liquefied natural gas formed principally of methane boiling at about -258° F. at atmospheric pressure. When used to transport large volumes of a liquefied natural gas or other liquids it is impractical to design a tank

2

to contain the liquid at pressures deviating widely from atmospheric pressure because the forces existing on the walls of the tank would be tremendous and incapable of being retained in a tank capable of economical or practical construction.

It has been common practice in polygonal tanks formed of flat plates to augment the structural strength of the tank by vertical stiffening beams or by a combination of vertical and horizontal beams but such arrangement has been found to be unacceptable for use in independent cargo containers designed to handle large volumes of liquid at very low temperature. This is due to the fact that the vertical beams not only become highly stressed in themselves but they also introduce additional stresses due to the thermal gradient in the tank in that they do not permit the bottom of the tank freely to contract or expand relative to the top of the tank without introducing bending moments in the vertical beams.

It is an object of this invention to provide tank structures of large capacity which are capable of serving as independent cargo containers mounted within a means of transportation such as a ship and which are strong enough to stand unbalanced pressures on the walls such as are brought about by movement in one or more planes of the transportation means.

Another object is to provide a tank structure of the type described which is capable of serving as an independent cargo container and which is capable of withstanding the stresses induced in the side walls of the tank by reason of thermal gradients existing in the tank, particularly when the tank is partially filled with a cold liquid.

These and other objects and advantages of this invention will hereinafter appear and for purposes of illustration, but not of limitation, an embodiment of the invention is shown in the accompanying drawing, in which—

Figure 1 is a perspective elevational view of a group of tanks embodying the features of this invention with portions broken away to show the interior construction thereof;

Figure 2 is a plan view of the bottom wall of a tank shown in Figure 1;

Figure 3 is a sectional view taken along the line 3—3 of Figure 1;

Figure 4 is a sectional view taken along the line 4—4 of Figure 1;

Figure 5 is a sectional view taken along the line 5—5 of Figure 1;

Figure 6 is a top plan view of the top wall of the tank shown in Figure 1 with portions broken away to show the inner structure thereof;

Figure 7 is a sectional view taken along the line 7—7 of Figure 6, and

Figure 8 is a sectional view taken along the line 8—8 of Figure 7.

It has been found in accordance with the practice of this invention that the desired performance characteristics in a polygonal tank of the type described for containing large volumes of liquid at a low temperature can be achieved by the combination which includes a plurality of vertically spaced apart, horizontally arranged, reinforcing and stiffening members which extend all about the interior wall of the tank and which are secured thereto for purposes of stiffening and reinforcing the walls of the tank to resist deformation under load and to transmit stresses operative on one wall to others adjacent thereto for distribution of load or stresses which might suddenly be brought about against one wall of the tank responsive to the pitch or roll of the ship. Such internal, horizontally arranged bracing members stiffen the individual walls of the tank while at the same time permitting

vertical temperature gradients to exist in the tank without inducing additional stresses characteristic of the previous use of vertical reinforcing members.

It has been found further that the desired performance characteristic in a polygonal tank of the type described for the transportation of large volumes of a cold liquid can be further improved by the use of a plurality of vertically spaced apart horizontally arranged reinforcing and stiffening members of the type described in combination with a plurality of horizontally disposed cross tie members extending angularly between the adjacent sections of the horizontally arranged stiffening and reinforcing members and spaced inwardly from the corner therebetween to interconnect the sections with stiff arms which operate in tension to resist deformation of the walls of the tank and to distribute stresses and load from one wall to the others adjacent thereto in a manner to relieve the walls of the full force of existing pressures.

It has been found that the performance characteristics of the independent cargo container can be still further improved by the inclusion with the combination described of horizontally arranged cross brace members extending crosswise between the mid-sections of the opposite walls of the tank to restrict the spaced relation between the walls and to provide pivot points about which wall deflections can take place to provide a combination of forces in effecting distribution of load and resistance to deformation.

Referring now to the drawings for a fuller description of the invention, a tank embodying the features of this invention is schematically illustrated as indicated by the numeral 10. The tank structure, which may be of various dimensions and shape, is formed with upright side walls 12 and 14, front and back walls 16 and 18, a bottom wall 20 and a top wall or cover 22. The elements are preferably formed of metal or alloy of high structural strength such as aluminum and alloys of aluminum, capable of use under the temperature conditions which may range to below -300° F.

In the assembled relation, the tanks 10 are confined by insulation and the like which separate the tanks from the walls of the ship and minimize the transfer of heat to the liquid contained in the tank.

A plurality of horizontally arranged, reinforcing and stiffening members 30 are secured, as by welding, in vertically spaced apart relation to the inner faces of the vertically disposed tank walls. The reinforcing of stiffening members 30, formed of rigid materials having high structural strength and preferably of metal plates, angle irons, I-beams, H-beams or the like, extend continuously about the interior surface of the tank to reinforce and stiffen the walls at vertically spaced apart portions. They operate to tie in the walls one with another in a manner to resist deformation under load and to distribute load substantially uniformly to all of the adjacent vertical walls of the tank. Because of the horizontal relationship of the reinforcing and stiffening members 30, as distinguished from the vertical arrangement of beams as heretofore employed, temperature gradients through the length of the tank will have little, if any effect on the existing stress relationships which would otherwise become developed in the tank. As a result, the tank having its vertical walls reinforced with the horizontally arranged reinforcing and stiffening members will be free to expand or contract without the introduction of stresses by vertical supporting or reinforcing means.

A further concept of this invention resides in the modification which makes use of cross ties 32, as illustrated in Figure 5 of the drawings. The cross ties extend angularly to interconnect the reinforcing and stiffening members 30 at the same level between the adjacent walls of the tank. These cross ties, which span the area between the adjacent sections of the reinforcing and stiffening members, comprise elongate metal or other stiff structurally strong members which are preferably spaced one

from the other inwardly from the corner defined by the adjacent walls. When more than one cross tie member is provided in each corner section, it is desirable to provide for a uniform spaced relation between the members and it is preferred to limit the distance from the corner so as not to bring the ends of the cross tie members beyond the centers of the adjacent walls thereby to avoid crossing over and interference with the cross tie members extending crosswise from other corners of the tank. Thus, in a rectangularly shaped tank, as illustrated in Figure 5, a section at the center of the tank wall of larger dimension will remain free of cross ties, as illustrated in Figure 5 of the drawings.

In addition to the horizontally arranged bracing and reinforcing members 30 and in addition to the cross ties 32 marked improvement in the characteristics of the tank will be secured by the use of cross brace members 34 and 36 which extend across the tank between opposite walls to tie in the walls in a manner to maintain a predetermined spaced relationship therebetween.

The cross ties take the balanced and unbalanced loads in the tank resulting from the ship's motion and, combined with the horizontal bracing and reinforcing members about the walls of the tank, give the tank the necessary structural strength to withstand shifting movements of the liquid in the tank due to the pitching and rolling of the ship. It will be apparent from the description that by the combination of the horizontal bracing members, cross tie members and cross bracing members, the tank is suitably constructed to provide, if necessary, for large unbalanced pressures against any wall of the tank while at the same time remaining substantially unaffected by the thermal gradients which might exist in the vertical plane of the tank. This is because the various horizontally arranged bracing and reinforcing members will, in general, be at the same level and therefore approximately at the same temperature.

From the theoretical standpoint, a new and novel combination of force members is provided for minimizing the effect of unusual stresses placed against any one or more walls of the tank. When load sufficient to cause deformation occurs, the force relationships developed through the described members are believed effective to place the adjacent cross ties under tension as the walls adjacent to the deformed wall are caused to flutter about the pivot at the center which is held against deflection by the cross brace members 34 and 36. The combination of forces in the cross tie members coupled with the stiffening and reinforcement available from the plurality of horizontally arranged stiffening and reinforcing members is effective to stabilize the tank under extreme load conditions thereby to make available a tank structure with maximum capacity and maximum strength coupled with minimum cost and materials.

Where the spaced relation between the ends of the inner most cross brace members is greater than the spaced relation between the ends of adjacent cross brace members in any one wall, as in the walls 12 and 14 of larger dimension in the illustrated tank, it is desirable to make use of a number of cross brace members at the center spaced apart from each other and from the ends of the cross ties 32 by an amount corresponding to the spaced relationship between the ends of the cross ties to continue the desired reinforcement throughout the wall of the tank for distribution of load, otherwise the central portion might become unbalanced in load with respect to the adjacent end portions. Instead of making use of a plurality of cross brace members 36^a and 36^b, the end of the cross brace member 36 may be provided with legs 38 and 40 that extend angularly outwardly to engage the wall 12, or corresponding portions of the attached stiffening and reinforcing plate 30, at the desired spaced apart points, as illustrated in Figure 5.

While the foregoing defines the important concepts embodied in the tank structure for strength and stability

under load, the following will describe the other elements illustrated in the tank of the drawings. The top wall 22 is provided with stiffening and reinforcing members on its underside by means of beams 42 which extend lengthwise of the tank in laterally spaced apart relation and a plurality of smaller beams 44 which extend crosswise of the tank in longitudinally spaced apart relation. The top wall 22 of the tank is provided with an opening 46 fitted with a cover 48 having a plurality of openings extending therethrough for the insertion of the various pipings used to introduce the liquid and to remove the liquid from the tank and to maintain various controls with respect to the pressure conditions existing within the tank. The numeral 50 indicates vertical members which, if desired, may be incorporated to tie in the top wall with the bottom wall of the tank.

The horizontal bracing members, the cross tie members and the cross brace members may be designed by conventional methods of stress analysis so that they will be of adequate strength and thickness to support such transmitted loads. It has been found that an aluminum alloy (particularly an aluminum-magnesium-chromium-manganese alloy) is well suited for the plates and the horizontal bracing members employed in the practice of this invention. This is because an aluminum-magnesium alloy gains strength and ductility at low temperatures and is not subject to brittle fracture. Such other materials as nickel-bearing steels would also be suitable; however, the aluminum-magnesium alloys appear to be the more economical for use. It will be understood that other metals of high structural strength capable of maintaining strength under the temperature conditions existing might also be used for the tank walls and for the various reinforcing and strengthening elements described.

The spacing of the horizontal bracing members may be determined by anyone skilled in the art by making a detailed stress analysis and by considering the fact that the spacing is dependent somewhat on the wall thickness. That is, the thicker the vertical walls of the tank, the farther apart the horizontal bracing members may be placed. As an example, in a tank 30' x 30' x 50' high, having a wall thickness of about $\frac{1}{2}$ ", it has been found desirable to space the horizontal bracing members 30 about 20 inches apart. In this example, the horizontal bracing members were 5" x 3" x $\frac{3}{8}$ " angles.

The structural arrangement of the tank embodying the features of this invention will enable the entire tank to behave as a stiff "box" sections that is fully capable of supporting the imposed loads with a minimum amount of material. The tank will be capable of withstanding large unbalanced pressures caused by the shifting of liquid within the tank while, at the same time, showing no effect of any stresses in the vertical walls of the tank which might be induced by a vertical thermal gradient throughout the tank.

It will be understood that changes may be made in the details of construction, arrangement and shape of the tank and the elements embodied therein without departing from the spirit of the invention, especially as defined in the following claims.

We claim:

1. A liquefied gas storage apparatus comprising a tank in which liquefied gas is stored in direct contact with the surfaces thereof at a temperature considerably below ambient temperature whereby the walls of the tank are subject to dimensional change in response to expansions and contractions due to wide temperature changes, comprising a completely enclosed tank of polygonal shape in horizontal cross-section having walls of a high strength, fluid impervious material which does not lose its strength at the temperature of the liquid and reinforcing means for the vertically disposed walls of the tank consisting essentially of horizontally disposed stiffening and reinforcing members joined to inner surfaces of the vertically disposed walls of the tank to extend substantially con-

tinuously thereabout and arranged in vertically spaced apart relation substantially throughout the height of the tank and integrally joined at their outer edges to the inner surfaces of the walls throughout their lengths to provide

5 vertically spaced apart, horizontally arranged sections reinforcing and stiffening the vertically disposed walls of the tank, cross tie members at each level of the stiffening and reinforcing members extending crosswise between adjacent vertically disposed walls of the tank with the

10 ends of the cross tie members secured in relatively uniformly spaced apart relation to the stiffening and reinforcing members for a distance short of the centers thereof, and cross brace members extending crosswise between opposite of the vertically disposed walls of the tank

15 and connected at their ends to the reinforcing and stiffening members in spaced apart relation from each other corresponding to the spaced relation between the ends of the cross tie members.

2. A liquefied gas storage apparatus of large capacity

20 comprising a tank in which liquefied gas is stored in direct contact with the surfaces thereof at a temperature differing widely from the ambient temperature whereby the walls of the tank are subject to dimensional change responsive to expansions and contractions due to temperature change, comprising a completely enclosed tank of polygonal shape in horizontal cross-section and formed with vertically disposed walls of a high strength, fluid impervious material which does not lose its strength at the temperature of the liquid and reinforcing and stiffening means for the vertically disposed walls of the tank consisting essentially of horizontally disposed stiffening and reinforcing members joined to the inner surfaces of the vertically disposed walls of the tank to extend substantially continuously thereabout and arranged in vertically spaced apart relation substantially throughout the height of the tank and integrally joined at their outer edges to the inner surfaces of the walls throughout their lengths to provide

25 vertically spaced apart, horizontally arranged sections reinforcing and stiffening the vertically disposed walls of the tank, and at least one horizontally disposed elongate cross tie member interconnecting the vertically disposed walls of the tank and extending angularly between and secured to the adjacent sections of the attached horizontally arranged and vertically spaced apart reinforcing and stiffening members.

3. A liquid storage tank as claimed in claim 2 in which the tank walls are formed of a metal having a relatively high coefficient of expansion and contraction and wherein the stiffening and reinforcing members are fixed to the inner face of the vertically disposed walls of the tank.

4. A tank as claimed in claim 2 in which, when more than one cross tie member is provided between adjacent sections of the attached horizontally arranged and vertically spaced apart reinforcing and stiffening members, the cross tie members are spaced one from the other inwardly from the corner for a distance less than that which positions the ends of the cross tie members beyond the centers of the adjacent wall sections.

5. A liquefied gas storage apparatus of large capacity

60 comprising a tank in which liquefied gas is stored in direct contact with the surfaces thereof at a temperature differing widely from the ambient temperature whereby the walls of the tank are subject to dimensional change responsive to expansions and contractions due to temperature change, comprising a completely enclosed tank of polygonal shape in horizontal cross-section and formed with vertically disposed walls of a high strength, fluid impervious material which does not lose its strength at the temperature of the liquid and reinforcing and stiffening means for the vertically disposed walls of the tank consisting essentially of horizontally disposed stiffening and reinforcing members joined to the inner surfaces of the vertically disposed walls of the tank to extend substantially continuously thereabout and arranged in vertically spaced apart relation substantially throughout the

height of the tank and integrally joined at their outer edges to the inner surfaces of the walls throughout their lengths to provide vertically spaced apart, horizontally arranged sections reinforcing and stiffening the vertically disposed walls of the tank, and a plurality of cross members interconnecting the opposite walls of the tank at their midsections at each of the levels corresponding to the reinforcing and stiffening members and secured at their ends to the corresponding horizontally disposed sections of the reinforcing and stiffening members.
